RAIL FOR LOCOMOTIVE STALLS

Filed Jan. 9, 1924

INVENTOR THOMAS CARDWELL,
by R. George Orwig, Attorney.

UNITED STATES PATENT OFFICE.

THOMAS CARDWELL, OF SEDALIA, MISSOURI.

RAIL FOR LOCOMOTIVE STALLS.

Application filed January 9, 1924. Serial No. 685,183.

My invention relates to improvements in rails for locomotive stalls.

The conventional, or present rail in locomotive stalls, or places for the repair of locomotives is the same as the standard running rail and the practice now, in the removal and replacement of such locomotive parts as springs, spring hangers, spring hanger pins, equalizers, equalizer pins, trailer brasses, or saddles, engine truck bases, engine truck wheels, trailer wheels and tires, by reason of such rails, requires the raising of the locomotive, by jacks, to provide freeing a selected part from the supporting rail for either vertical or lateral movement relative to the locomotive proper and the running rails.

The object of my invention is to provide a rail, for use in connection with the pair of the running gear of rolling stock, and more particularly to repairs on locomotives wherein either vertical or lateral movement of a driving, truck or trailer wheel is required, which rail comprises a removable and replaceable tread, in the plane of the running tread of adjacent standard rails, over which wheels may travel as ordinarily, and which rail also comprises a second tread, or surface, resident in a plane below the running tread, which latter tread constitutes a support to which a wheel may drop and be laterally moved with relation to the locomotive proper and running rail, upon a bodily removal of the first mentioned tread.

My improvements consist in the novel construction, arrangement and combination of parts as hereinafter fully, clearly and concisely described, definitely pointed out in my claims and illustrated by the accompanying drawing (1 sheet) in which—

Fig. 1 is a perspective view showing a rail, constructed in accordance with my invention, as employed for a running rail.

Fig. 2 is a similar view showing the rail as employed for a repair rail.

Fig. 3 is a diagrammatical elevation showing by solid lines, the rail and a fragment of a wheel thereover in position for repair, and by dotted lines the rail and a fragment of a wheel in running position.

Fig. 4 is an enlarged transverse sectional elevation, taken on a line indicated 4—4 of Fig. 1.

Fig. 5 is a view similar to Fig. 4 with the removable tread omitted as in Fig. 2.

Fig. 6 is an enlarged transverse sectional elevation, taken on a line indicated 6—6 of Fig. 1.

Referring, by numerals, to the drawing, 6 and 7 designate fragments of standard running rails and 8 the ties, or sleepers, therefor. Between the ends of the rails 6 and 7 I position the body of my improved rail 9, having in its upper face a groove, or channel 10, and on each side of the groove a surface 11, a portion, at least, of which occupies a plane lower than the plane of the treads, or balls, of the rails 6 and 7.

For the securing of the rail 9 against movement relative to the rails 6 and 7 I prefer to employ plates, such as 12 and 13, formed as integral projections of the body of the rail 9, and similarly shaped plates 14 and 15, which are removably and replaceably connected to the rail 9, plates 12 and 13 and rails 6 and 7, by means such as the bolts 16, after the fashion of the common fish plates.

By preference, and as shown, the surfaces 11 are curvilinear throughout the length of the body of the rail 9, and at each end meet, or are flush, with surfaces 17 (the tops) of the plates 12, 13, 14 and 15, which surfaces 17 reside substantially in the plane of the flanges of the wheels of rolling stock (not shown) whereby to constitute a support for the wheels, at times, as hereinafter made clear.

By further preference the groove, or channel 10, is of a width less than the width of the heads of the rails 6 and 7 and there is formed at each end of each surface 11, intersecting the groove 10, a seat such as 18, as best shown in Figs. 2 and 4, whereby there may be fitted to the rail 9, a tread, or rail head 19, whose ends are rested in said seats 18, whereby to hold it against lateral displacement relative to the rails 6 and 7 and which is of a length equaling the spacing of the rails 6 and 7, to abut thereagainst at each end whereby it is held against creeping, or lengthwise movements. On the underneath portion of the tread, or head 19, is a web, or tang 20 shaped to fit the groove 11 and designed to bridge the tread 19 between the rails 6 and 7.

By way of illustrating the use and advantages of my improved rail, let it be assumed there is requirement for the repair of a locomotive part, such as a broken, or defective spring of a truck. Ordinarily the

locomotive is brought to a stall, having standard running rails, and the locomotive raised, by jacks, to permit the truck, to be repaired, to be lowered so that the defective spring may be removed and replaced.

By the employment of a rail constructed in accordance with my invention, the locomotive may be moved, as desired, assuming the tread 19 to be in place, as shown in Fig. 1 and by dotted lines in Fig. 3, to locate, or "spot" the wheel under the defective spring, near one of the surfaces 17; the tread 19 is then bodily removed and the locomotive moved, in which movement the flange of the wheel, of the truck having the defective spring, is first supported on the surface 17, then moved to the surface 11, in which latter movement the wheel and hence the truck is lowered and ready for repair.

Obviously the equipment, operating and maintenance cost of my rails as compared with the jack equipment is reduced materially, and practically to a minimum. Obviously further the time required to move the tread 19 and "roll" the locomotive is much shorter than the time required to place and operate the present jack equipment, to the end that the locomotive is restored to service in much shorter time.

30 I claim:

1. A rail comprising a body portion, plates formed integral therewith and similar separate plates for securing the body to adjacent running rails, a tread portion, formed distinct from said body portion, means for securing the tread portion against movements relative to the body portion, said body portion having its upper surface in a lower plane at its middle than at its ends, and a web carried by the tread portion for supporting the tread portion over the body portion.

2. An apparatus of the class described, for installation between the ends of a pair of running rails, comprising a pair of oppositely inclined surfaces, whose outer ends occupy planes in which they will be engaged by the wheel flanges of rolling stock in their normal running plane and the inner ends of which surfaces occupy planes lower than the normal running plane of the said wheel flanges.

3. A rail of the kind described having a removable upper portion adapted to support the wheels of rolling stock in the plane of the wheel supporting surfaces of a continuous line of rails, and a body portion having a depressed wheel supporting surface adapted, upon removal of said removable portion, to support said wheels in a plane beneath the plane of the wheel supporting surfaces of said line of rails.

4. A rail for use in connection with the repair of rolling stock, comprising a body, adapted to be secured in line with and be-

tween the ends of a pair of running rails, said body having a surface whose ends occupy positions wherein they will be engaged by the wheels of rolling stock in their normal, running plane and which surface, between its ends, drops to a lower plane.

5. A rail for use in connection with the repair of rolling stock, comprising a body, adapted to be secured in line with and between the ends of a pair of running rails, said body having a surface whose ends occupy positions wherein they will be engaged by the wheels of rolling stock in their normal, running plane and which surface, between its ends, drops to a lower plane, and a removable and replaceable element, adapted to be secured in line with and between the ends of said running rails, said element having a surface above the recited surface of said body for engagement by the wheels of rolling stock, which surface of the removable element throughout its length occupies a plane substantially that of the normal running plane of the wheels of rolling stock.

6. A rail of the class described adapted to be secured in line with and between the ends of a pair of running rails and having a wheel flange-engaging surface laterally removed from the treads of said running rails, said surface having its ends in the plane of wheel flanges as supported upon the running rails and its middle portion in a lower plane.

7. A rail of the class described adapted to be secured in line with and between the ends of a pair of running rails and having a wheel flange-engaging surface laterally removed from the treads of said running rails, said surface having its ends in the plane of wheel flanges as supported upon the running rails and its middle portion in a lower plane, and a removable and replaceable element disposed in line with said running rails over the recited rail and having a substantially straight tread section.

8. A railroad track comprising continuous lines of rails whose wheel supporting surfaces have depressions therein, and removable sections fitting said depressions and having wheel supporting surfaces disposed in the plane of the main wheel supporting surfaces of said rails.

9. A rail of the character described having a longitudinally curved recess formed intermediate its ends and a removable section adapted to be received in said recess.

10. A rail of the character described having a recess formed intermediate its ends, reinforcing means adjacent said recess, and a removable section adapted to be received within the recess.

11. A rail of the character described having a longitudinally curved recess formed intermediate its ends, a removable section

adapted to be received in said recess, and means for preventing displacement of the removable section relative to the rail.

12. A rail of the character described having a recess formed intermediate the ends and openings within the recess, a removable section adapted to be received within the recess, and projections carried by the removable section and adapted to be received in the openings.

13. A rail of the character described having a longitudinally curved recess intermediate the ends, and a removable section adapted to be received in said recess, the removable section being curved to conform to the curvature of the recess.

14. A rail of the character described having a longitudinally curved recess intermediate the ends, and a removable section adapted to be received within the recess, 20 said removable section having a longitudinally curved projection to conform to the curvature of the recess.

15. A rail adapted for use in repairing locomotives or the like having a normally 25 level surface for supporting the wheels of the locomotive and a detachable section adapted to be removed to provide a recess over which the wheels may be positioned and allowed to be lowered.

THOMAS CARDWELL.
